UNITED STATES PATENT OFFICE.

JONAS NORTHROP, OF HOPEDALE, MASSACHUSETTS, ASSIGNOR TO DRAPER COMPANY, OF HOPEDALE, MASSACHUSETTS, A CORPORATION OF MAINE.

FILLING-REPLENISHING LOOM.

SPECIFICATION forming part of Letters Patent No. 726,978, dated May 5, 1903.

Application filed December 22, 1902. Serial No. 136,090. (No model.)

To all whom it may concern:

Be it known that I, JONAS NORTHROP, a subject of the King of Great Britain, and a resident of Hopedale, county of Worcester, State of Massachusetts, have invented an Improvement in Filling-Replenishing Looms, of which the following description, in connection with the accompanying drawings, is a specification, like characters on the drawings representing like parts.

This invention relates more particularly to looms which are equipped with some form of mechanism which is dependent for its proper operation upon a certain location or definite position of the shuttle in the shuttle-box, the automatic operation of such mechanism when the shuttle is not in such definite or certain position causing injurious wear and tear and not infrequently serious breakage.

The mechanism which provides automatically a running shuttle with filling is a well-known form of apparatus of the character above referred to, and to those conversant therewith it will be manifest that if the shuttle is not in proper replenishing position the transfer of a supply of filling thereto is liable to be accompanied by great and injurious strain upon the transferring instrumentality or the shuttle, or both, so that parts are sometimes seriously damaged and their life is diminished materially.

Means have been devised and operated with great success to detect the failure of the shuttle to enter the shuttle-box far enough and to prevent the filling-replenishing operation at such time; but such means does not detect overrunning of the shuttle—i. e., its passage beyond the proper definite position in the shuttle-box. If, for instance, the picker is badly worn, the shuttle may go so far into the box that when a filling-carrier is transferred by the replenishing mechanism it will come down upon the shuttle itself back of the opening therein and a smash occurs.

My present invention has for its main object the production of means to prevent the operation of such automatic mechanism in a loom as is dependent upon a definite position of the shuttle if the latter either fails to attain or passes beyond such definite position in the shuttle-box. In other words, if the

shuttle is too far in or too far out of the shuttle-box the operation of the mechanism intended to coact with the shuttle will be prevented, thereby obviating wear, strain upon the parts, and breakage.

Another object of my invention is to provide for a more accurate operation of the shuttle-position-indicating means, so that the same shall be free from the effect of variations in the stroke of the lay due to wear in different parts of the loom. This I attain by mounting the device which coöperates with the shuttle preferably upon the shuttle-box itself, and by locating such device at or near the outer end of the box I obviate any shortening or cutting away of the front box-wall at its inner end, which is very detrimental to the proper guidance of the shuttle when it is thrown.

These and other novel features of my invention will be described in detail in the subjoined specification and particularly pointed out in the following claims.

Figure 1 is a right-hand side elevation of a sufficient portion of a loom to be understood provided with filling-replenishing mechanism and having one embodiment of my present invention applied thereto, the lay being back and the filling-feeder being shown in section. Fig. 2 is a similar view of some of the parts of the apparatus shown in Fig. 1, but taken at the instant of filling replenishment, the shuttle being in proper position in the shuttle-box for such operation to be effected. Fig. 3 is a top or plan view of the replenishing shuttle-box, showing the shuttle-detector and the position assumed thereby when the shuttle is properly positioned in the box. Fig. 4 is a front elevation of the parts shown in Fig. 3; and Fig. 5 is a detail, partly in section, on the line 5—5, Fig. 4, showing the manner of preventing the replenishing operation when the shuttle is in improper position in the shuttle-box.

I have chosen to illustrate my invention in connection with mechanism adapted to replenish or supply the shuttle with filling at the proper time, such as when filling fails or has been exhausted to a predetermined extent, provided at such time the shuttle is properly positioned in the shuttle-box in co-

operative relation to the replenishing mechanism.

The loom-frame A, breast-beam A¹⁰, having mounted upon it at one side, herein shown as the right-hand side of the loom, automatic filling-replenishing mechanism comprising, essentially, a rotatable feeder F, adapted to contain the supplies of filling (shown as filling-carriers b) and rotating on an axis a, the transerrer f', fulcrumed on a fixed stud f and having a depending arm f³, the lay A³, having a bunter C² rigidly secured thereto, and means for effecting step-by-step rotation of the feeder to present the filling-supplies b one by one into position to be transferred to the shuttle may be and are all as shown in United States Patent No. 664,790, dated December 25, 1900. The replenishing operation whereby a filling-supply is transferred from the feeder to the shuttle, is effected when a change occurs in the condition of the filling in use—as, for instance, its exhaustion, entirely or to a predetermined extent, or its breakage—and when such a change occurs the rock-shaft d' is turned in the direction of the arrow 65, as in the patent referred to, said rock-shaft having fast upon it an arm d^X, which is held in the position shown in Fig. 1 by a spring d³. As in said patent, a rocker-stud m¹² is mounted on the down-turned end f³ of the transerrer, said stud being normally turned (by a spring not herein shown) in the direction of the arrow 12, Fig. 1, an arm m¹³, secured to the stud, having adjustably secured upon it a notched dog m¹⁵, provided with a lateral lug m¹⁴, extended toward the loom side in the present embodiment of my invention, and a second lug m¹⁶ is carried by the dog, but located nearer its outer or front end and turned oppositely to the lug m¹⁴. The lug m¹⁶ is beveled, as shown in Figs. 1, 2, and 5, for a purpose to be hereinafter described. The arm d^X is herein shown as upturned at its inner end and then extended outwardly, as at d^{2X}, to rest against the lug m¹⁴. When the loom is running properly, the tendency of the dog m¹⁵ to rise is overcome by the more powerful spring d³, the extension d^{2X} of the arm d^X bearing against the lug m¹⁴, as shown in Fig. 1.

When a change or replenishment of filling is to be effected, the shaft d' is rocked in the direction of the arrow 65, swinging up the rocker-arm d^X and its extension, and thereby permitting the stud m¹² to turn and raise the notched end of the dog m¹⁵ into the path of and to be engaged by the bunter C² as the lay beats up, and if the replenishing operation is to be completed the transerrer is thereby depressed to transfer a supply of filling from the feeder to the shuttle.

The rock-shaft d' forms a part of the means for controlling the time of operation of the replenishing mechanism, as will be well understood by those skilled in the art.

The proper operation of the replenishing mechanism can only be effected when the

shuttle is in a certain definite position in the shuttle-box at the instant of transfer in order that the filling-supply may be properly inserted in the opening provided therefor in the shuttle and to be engaged by suitable holding means carried by the shuttle. If the shuttle in entering the box fails to reach such definite position or overruns or passes beyond such position, it will be manifest that complete replenishing operation of the replenishing mechanism will result in undue wear upon the parts, and very frequently in actual practice it results in smashing the shuttle, the filling-carrier being transferred or a part of the replenishing mechanism itself, any or all. As the replenishing mechanism is thus dependent for its proper operation upon a definite position of the shuttle in the shuttle-box, I have provided novel and effective means for preventing such operation of the replenishing mechanism unless the shuttle is in the required definite position.

The front wall b' of the replenishing shuttle-box B^X is provided near its outer end with a forwardly - extended shelf or bracket b², which carries a vertical fulcrum-stud b³, on which is mounted the hub h^X of a shuttle-detector, shown as a lever of the first class, the outer lever-arm h being turned rearwardly to extend into the shuttle-box in the path of the shuttle through an opening b³⁰, made in the front box-wall b'. At its inner end the arm h is provided with a cushion or pad h', of leather or other suitable non-metallic material, to impinge against the shuttle when the latter is boxed. The other and longer arm h² of the detector is extended toward the center of the lay and is provided with a socketed portion h³ to receive one end of a spring s^X, the other end of the spring bearing against the box-wall b', as clearly shown in Fig. 3. The spring acts to normally move the outer end h of the detector into the path of the shuttle. The extremity of the arm h² is reduced in diameter and preferably made cylindrical to form a finger h⁴, which slides in a transverse slot or groove 25 in a depending extension c^X, herein shown as secured to or forming a part of the outer end of the bunter C², the slot or groove forming a guide for the finger. On the outer face of the extension c^X and near its lower end I have fulcrumed at c a dog-controller c', shown as an arm extended toward the front of the loom and notched at its free end, said dog-controller being adapted to at times be moved into position to engage the lug m¹⁶ on the dog. The dog-controller is provided near its fulcrum with a cam-slot, shown in Figs. 1, 2, and 5 as having a high portion 30 and low portions 31 32 at its ends in front of and behind the high portion, respectively, the finger h⁴ passing through the cam-slot and into the guide slot or recess 25, as clearly shown in Fig. 3. When the shuttle-box is empty, the spring s^X turns the shuttle-detector on its fulcrum b³, moving its end h into the shuttle-box and moving the finger h⁴ outward and into the

low part 31 of the cam-slot of the dog-controller c' , as shown in Fig. 1, and when the lay beats up the notched end c^2 of the dog-controller will be above the lug m^{16} . When the shuttle S, Fig. 3, enters the replenishing shuttle-box, the shoulder at the leading end of the shuttle engages the cushioned end of the detector and swings the latter on its fulcrum b^3 , and when the shuttle is properly positioned or assumes a certain definite position in the shuttle-box the finger h^4 will be swung rearwardly onto the high part 30 of the cam-slot to thereby depress the dog-controller into the position shown in Fig. 2.

Unless filling-replenishing is to be effected it will be manifest that the exact or definite positioning of the shuttle in the shuttle-box B^X is immaterial; but if the shuttle does not occupy such definite position when a transfer of filling would otherwise take place the detector detects such improper positioning and through the dog-controller prevents co-operation of the dog m^{15} and bunter C^2 and a transfer of filling—that is, a complete replenishing operation of the replenishing mechanism—will not be effected on that pick.

When a transfer of filling is to be effected, the rock-shaft d' is turned in the direction of the arrow 65, and by the lifting of the arm d^X the dog m^{15} is permitted to swing upward on the stud m^{12} into the path of the bunter C^2 , and if at such time the shuttle is properly positioned in the box B^X the dog-controller c' will be rendered inactive by or through the shuttle-detector as the lay beats up, and, as shown in Fig. 2, the dog-controller will then pass beneath the lug m^{16} . In other words, the dog-controller is maintained inactive by the shuttle-detector when the finger h^4 is at the high part 30 of the cam-slot. If now the shuttle in entering the shuttle-box B^X fails to reach its definite position proper for replenishing, the detector will not be moved far enough to withdraw the finger h^4 from the low part 31 of the cam-slot and the dog-controller c' will be in its active position, as shown in Fig. 5, and as the lay beats up the notched end c^2 of the dog-controller will engage the lug m^{16} and will depress the dog m^{15} below the bunter C^2 , as shown in Fig. 5, so that a transfer of filling to the shuttle will not be effected, said dog turning on the stud m^{12} . On the other hand, if the shuttle overruns or passes beyond the definite replenishing position in the replenishing-box on the pick when replenishing would otherwise be effected the shuttle-detector will be turned on its fulcrum b^3 so far that the finger h^4 will be swung inward and into the low part 32 of the cam-slot of the dog-controller, and the latter will then be maintained in the position shown in Fig. 5, and as the lay beats up the lug m^{16} on the dog m^{15} will be engaged, as has been before described, and the dog will be turned down beneath or out of the path of the bunter C^2 , and replenishing will not be effected.

It will be understood from the foregoing

description that if the replenishing mechanism is brought into condition to supply the shuttle with filling by or through the controlling means described such replenishment can be effected only when the shuttle is in the proper definite position for replenishment—that is, when the finger h^4 is at the high part of the cam-slot of the dog-controller and the relative position of the parts is such as is illustrated in Fig. 2.

By mounting the shuttle-detector on the shuttle-box itself, as herein described, I obtain very accurate results, as the accuracy of operation of the detector is no longer subjected to the action of changes which may come from variations in the stroke of the lay due to wear or otherwise.

So far as I am aware, it is broadly new to provide means which will prevent the complete operation of filling-replenishing mechanism if the shuttle is too far in the shuttle-box or too far out of it, and accordingly my invention is not restricted to the particular means herein shown and described for effecting such result.

Former shuttle-detectors which have been moved toward or across the shuttle-path at or near the inner end of the shuttle-box have frequently injured the shuttle when the latter has not been properly positioned by scraping it more or less. This scraping or injury to the shuttle is impossible in my present invention, as the non-metallic cushion or pad on the contact portion of the detector absolutely prevents such action.

By locating the detector at or near the outer end of the shuttle-box I have obviated cutting away or shortening the front box wall or plate at its inner end, such shortening of the box-plate detracting from the proper and necessary guidance of the shuttle when it is thrown from the box. It will also be observed that in my present invention the shuttle-detector is not only controlled and operated by or through the shuttle itself, but the detector is also wholly independent of the means which controls the time of operation of the replenishing mechanism.

The part of the detector which co-operates with the shuttle tends to assist in checking the motion of the latter, inasmuch as it is located near the end of the stroke of the shuttle.

The shuttle S (shown in Fig. 3) is of well-known construction to those skilled in the art, it being provided with suitable holding means or jaws j to engage the head of the filling-carrier, and at its other end the shuttle is provided with an automatically self-threading device T of any suitable or desired form.

Some looms are equipped with means which permit the loom to turn over if the shuttle fails to reach the box and without damage to the warp; but heretofore in such a loom the replenishing mechanism would operate to transfer filling-carriers to the empty shuttle-box and exhaust the hopper if the loom should continue to turn over for a sufficient period.

It will be manifest, however, that such operation of the replenishing mechanism cannot be effected even if the loom be equipped with means which permit it to turn over, for if the shuttle does not engage and move the shuttle-detector at all the dog-controller *c* will remain in its active position, and so prevent the transfer of filling from the hopper or feeder to the empty shuttle-box.

10 I have herein shown and described one practical embodiment of my invention, and the same may be modified or rearranged in various particulars by those skilled in the art without departing from the spirit and 15 scope of my invention.

Having fully described my invention, what I claim as new, and desire to secure by Letters Patent, is—

1. In a loom, a shuttle, a lay having a shuttle-box, a shuttle-detector, mechanism dependent for its proper operation upon a definite position of the shuttle in the shuttle-box, and means governed by or through coöperation of the detector with the leading end of 25 the shuttle to prevent such operation of said mechanism when the shuttle has failed to attain or has passed beyond such definite position.

2. In a loom, a shuttle, a lay having a shuttle-box, a shuttle-detector mounted on the lay, mechanism adapted to coöperate with the shuttle when the latter occupies a definite position in the shuttle-box, and means governed by or through coöperation of the detector with the leading end of the shuttle to prevent coöperative action of said mechanism when the shuttle has failed to attain or has passed beyond such definite position.

3. In a loom, a shuttle, a lay having a shuttle-box, a shuttle-detector mounted on the shuttle-box near its outer end to detect the position of the shuttle therein, mechanism adapted to coöperate with the shuttle when the latter occupies a definite position in the 45 shuttle-box, and means governed by or through the detector to prevent coöperative action of said mechanism with the shuttle when the latter has failed to attain or has passed beyond such definite position.

5. In a loom, a shuttle, a lay having a shuttle-box, a shuttle-detector to coöperate with and be positioned by the leading end of the incoming shuttle, mechanism adapted to coöperate with the shuttle when the latter occupies a definite position in the shuttle-box, and means governed by or through the detector to prevent coöperation of said mechanism with the shuttle when the latter fails to occupy such definite position in the 55 shuttle-box.

6. In a loom, a lay having a shuttle-box, a shuttle, mechanism to replenish automatically the shuttle with filling when the shuttle occupies a definite position in the shuttle-box, and means to prevent the replenishing operation of said mechanism, said means including a detector moved into active position by

the shuttle when the latter is improperly positioned.

7. In a loom, a lay having a shuttle-box, a shuttle, mechanism to replenish automatically the shuttle with filling when the shuttle occupies a definite position in the shuttle-box, and means to prevent the replenishing operation of said mechanism, said means including a detector located near the outer end of the shuttle-box and moved into active position by the shuttle when the latter is improperly positioned.

8. In a loom, a lay having a shuttle-box, a shuttle, mechanism to replenish automatically the shuttle with filling when the shuttle occupies a definite position in the shuttle-box, and means to prevent the replenishing operation of said mechanism, said means including a detector mounted on the shuttle-box and moved into active position by the shuttle when the latter fails to attain or overruns such definite position.

9. In a loom provided with automatic filling-replenishing mechanism, a lay having a shuttle-box, a shuttle, and means, including a member moved by the incoming shuttle, to prevent the replenishing operation of said mechanism when the shuttle fails to attain or overruns proper position for replenishment.

10. In a loom provided with automatic filling-replenishing mechanism, a lay having a shuttle-box, a shuttle, and means, including a member mounted on the lay and moved by the incoming shuttle, to prevent the replenishing operation of said mechanism when the shuttle stops short of replenishing position.

11. In a loom provided with automatic filling-replenishing mechanism, a lay having a shuttle-box, a shuttle, and means, including a shuttle-detector mounted adjacent the outer end of the shuttle-box and moved by the incoming shuttle, to prevent the replenishing operation of said mechanism when the shuttle overruns or stops short of proper replenishing position.

12. In a loom, a lay having a shuttle-box, a shuttle, a shuttle-detector near the outer end of the shuttle-box to coöperate with the leading end of the incoming shuttle, mechanism to supply filling to the shuttle when the latter occupies a definite position in the shuttle-box, and means governed by or through the detector to prevent filling-supply when the shuttle fails to occupy such definite position in the shuttle-box.

13. In a loom, a lay having a shuttle-box, a shuttle, a shuttle-detector mounted on the front box-wall and movable by engagement with the incoming shuttle into active position

- when the shuttle is improperly positioned for filling replenishment, automatic filling-replenishing mechanism, and means rendered effective by the detector when actively positioned to prevent the replenishing operation of said mechanism.
14. In a loom, a lay having a shuttle-box and a bunter, a shuttle, filling-replenishing mechanism, including a dog movable automatically into the path of and to coöperate with the bunter, to effect the operation of said mechanism, a shuttle-detector moved positively and rendered active by the shuttle when the latter is improperly positioned for replenishing, and means to prevent coöperation of the dog and bunter when the detector is rendered active.
15. In a loom, a lay having a shuttle-box and a bunter, a shuttle, filling-replenishing mechanism, including a dog movable automatically into the path of and to coöperate with the bunter, to effect the operation of said mechanism, a shuttle-detector mounted on the shuttle-box and adapted to be moved by the shuttle, and means normally in operative condition and governed by the detector, to prevent coöperation of the dog and bunter, positioning of the detector when the shuttle is properly boxed for replenishing rendering said means inoperative.
16. In a loom, a lay having a shuttle-box and a bunter, a shuttle, filling-replenishing mechanism, including a dog movable automatically into the path of and to coöperate with the bunter, to effect the operation of said mechanism, a spring-controlled detector adapted to be engaged and moved by the incoming shuttle, a finger connected with the detector, and a dog-controller movably mounted on the lay and having a cam-slot in which the finger moves, shuttle-induced movement of the detector causing the finger to operatively position the controller when the shuttle is improperly boxed for replenishing, to engage and move said dog and prevent its co-operation with the bunter.
17. A lay having a shuttle-box thereon provided with a front wall apertured near its outer end, a spring-controlled shuttle-detector mounted on said wall and extending through the aperture into the path of the shuttle, to be moved thereby and positioned according to the final position of the shuttle when boxed, a shuttle, mechanism to replenish automatically the shuttle with filling, and means governed by said detector to prevent the replenishing operation of said mechanism when the shuttle is improperly boxed for replenishing.
18. In a loom, filling-replenishing mechanism, including a transfferer and a dog carried thereby, the lay having a shuttle-box and a bunter thereon, controlling means for said mechanism, to move the dog into the path of and to coöperate with the bunter, a movable dog-controller on the lay and normally inoperative, a shuttle, a shuttle-detector moved by engagement with the incoming shuttle, and a connection between said controller and detector, positioning of the latter by the shuttle when improperly boxed for replenishing causing said controller to act upon the dog and prevent its coöperation with the bunter.
19. In a loom, a lay having a shuttle-box, a shuttle, a shuttle-detector pivotally mounted on the shuttle-box to coöperate with the leading end of the incoming shuttle, a spring to move the detector into the path of the incoming shuttle, mechanism to supply the shuttle with filling when properly boxed, and means governed by or through the detector to prevent filling-supplying operation of said mechanism when the shuttle is improperly positioned in the shuttle-box to receive a supply of filling.
20. In a loom, a lay having a shuttle-box, a shuttle, mechanism to replenish automatically the shuttle with filling, means moved by the shuttle to indicate the position thereof in the shuttle-box, and an instrumentality controlled by such means to prevent replenishing operation of said mechanism when said means indicates that the shuttle is improperly boxed for replenishing.
21. In a loom, a lay having a shuttle-box, a shuttle, mechanism to replenish automatically the shuttle with filling, means moved by the shuttle to indicate the position thereof in the shuttle-box, and an instrumentality controlled by such means to prevent replenishing operation of said mechanism when the shuttle overruns replenishing position in the shuttle-box.
22. In a loom, a lay having a shuttle-box, a shuttle, mechanism to replenish automatically the shuttle with filling, a shuttle-detector having a non-metallic contact portion to be engaged and moved by the incoming shuttle to indicate its position in the box, and means controlled by the detector to prevent replenishing operation by said mechanism when said detector is moved by the shuttle to indicate improper boxing thereof for replenishing.
23. In a loom, a lay having a shuttle-box, a shuttle, a shuttle-detector, mounted on the shuttle-box and having a cushioned contact portion in the path of the incoming shuttle, mechanism dependent for its proper operation upon a definite position of the shuttle in the shuttle-box, and means governed by or through shuttle-induced movement of the detector to prevent such operation of said mechanism when the detector indicates failure of the shuttle to attain, or overrunning of, such definite position in the box.
24. In a loom provided with automatic filling-replenishing mechanism, means to control the time of its operation, a lay having a shuttle-box, a shuttle, a detector to coöperate with the leading end of and detect the position of the incoming shuttle when boxed, said detector being wholly independent of said controlling means, and means governed by or through said detector to prevent the re-

plenishing operation of said mechanism when the shuttle is improperly positioned in the shuttle-box.

25. In a loom provided with automatic filling-replenishing mechanism, means, including a rock-shaft, to control the time of its operation, a lay having a shuttle-box, a shuttle, a shuttle-detector wholly independent of said rock-shaft and the parts controlled thereby and adapted to detect improper positioning of the shuttle when boxed, and means governed by or through said detector to prevent the replenishing operation of said mechanism when the shuttle is improperly positioned for replenishing.

26. In a loom provided with automatic filling-replenishing mechanism, means, including a rock-shaft, to control the time of its operation, a lay having a shuttle-box, a shuttle, and means wholly independent of said rock-shaft and the parts controlled thereby and governed by the shuttle independently of filling therein to prevent replenishing operation of said mechanism when the shuttle is improperly positioned for replenishing.

27. In a loom, a lay having a shuttle-box, a shuttle, a shuttle-detector, mechanism dependent for its proper operation upon a definite position of the shuttle in the shuttle-box, and wholly independent of the filling in the shuttle, and means governed by or through the detector to prevent such operation of said mechanism when the shuttle has passed beyond such definite position.

28. In a loom, a lay having a shuttle-box, a shuttle, mechanism to replenish automatically the shuttle with filling, means moved by the shuttle entering the box to indicate the position of the shuttle therein, and an instrumentality controlled by such means to prevent replenishing operation of said mechanism upon failure of said means to be moved by the shuttle.

In testimony whereof I have signed my name to this specification in the presence of two subscribing witnesses.

JONAS NORTHROP.
